STETHOSCOPE AND STAND

Stephen G. Hauser, Tarzana, Calif., assignor to Baxter
Laboratories, Inc., Morton Grove, Ill.

Filed Sept. 15, 1972, Ser. No. 289,505

Term of patent 14 years

Int. Cl. D24—02

U.S. Cl. D83—12 R

Fig. 1

Fig. 2

Fig. 3

Fig. 4

Fig. 5

Fig. 6

Fig. 7

FIG. 1 is a perspective view of the stethoscope and supporting stand, illustrating my new design;

FIG. 2 is a top plan view of the apparatus of FIG. 1;

FIG. 3 is a right side elevational view of the apparatus of FIG. 1;

FIG. 4 is a front elevational view of the apparatus of FIG. 1;

FIG. 5 is a rear elevational view of the same apparatus;

FIG. 6 is a bottom plan view of the supporting stand; and

FIG. 7 is an exploded view in perspective of the stethoscope, ear plugs, amplifier case and supporting stand.

I claim:

The ornamental design for a stethoscope and stand, substantially as shown and described.
